UNITED STATES PATENT OFFICE.

HENRY C. HERR, OF PITTSBURGH, PENNSYLVANIA, ASSIGNOR, BY MESNE ASSIGNMENTS, TO SOUTH SIDE TRUST COMPANY, TRUSTEE, OF PITTSBURGH, PENNSYLVANIA, A CORPORATION OF PENNSYLVANIA.

MACHINE FOR FORMING PAPER OR FIBER PACKAGES.

1,186,985.

Specification of Letters Patent. Patented June 13, 1916.

Application filed October 21, 1913. Serial No. 796,446.

To all whom it may concern:

Be it known that I, HENRY C. HERR, a citizen of the United States of America, residing at Pittsburgh, in the county of Allegheny and State of Pennsylvania, have invented certain new and useful Improvements in Machines for Forming Paper or Fiber Packages, of which the following is a specification, reference being had therein to the accompanying drawings.

The invention relates to machines of that type employed for the formation of a cylindrical drum or package by the winding of a plurality of plies of paper or fiber stock.

It is the object of the present invention to obtain a construction adapted for the formation of a package in which the paper or fiber stock is reinforced by a metallic insert.

To this end the invention consists in various features of construction as hereinafter set forth.

In the drawings: Figure 1 is a side elevation of the machine. Fig. 2 is a plan view thereof. Fig. 3 is a vertical longitudinal section. Fig. 4 is a cross section, showing parts of the mechanism in end elevation. Fig. 5 is a plan view of a portion of the operating mechanism. Fig. 6 is a longitudinal section through the winding drum. Fig. 7 is a section showing a portion of Fig. 3 with the parts in different position of adjustment. Fig. 8 is a sectional view of a detail.

A is the frame of a machine which is provided at one end with a table B for supporting the metallic reinforcement.

C is a winding drum mounted upon the frame above the plane of the table B.

D are feed rolls for delivering a continuous strip of paper over a table E which delivers it tangentially to the upper side of the winding drum C. This winding drum comprises a plurality of collapsible segments C', C'', etc., which are connected through suitable mechanism to the drum-shaft F. The detail construction of this mechanism, as well as the detail construction of various other parts of the machine is similar to my prior Patent No. 823,276, June 12, 1906, and I will therefore omit description of the same excepting so far as necessary to the understanding of the novel features of the present construction.

The essential operations performed by the machine are, first, the engagement of the paper strip with the winding drum and the winding of one or more plies thereon; second, the delivery of the metallic reinforcing sheet to the drum between plies, and the winding of the same therebetween; and third, the coating of the adjacent surfaces of the paper and metallic reinforcement with a suitable adhesive, which will firmly bind the same together. Another feature of the construction is a cut-off which is operated to sever the paper strip when the required length has been fed, and further a suitable timed drive-mechanism by which the various instrumentalities are operated in proper sequence.

Drive mechanism.—For driving the machine, motion is communicated from any suitable source to a pulley G which drives a pinion G' intermeshing with the gear-wheel G² coupled by a clutch G³ with a shaft G⁴, having a pinion G⁵ intermeshing with a gear-wheel G⁶ upon the main shaft G⁷ of the machine. Upon the opposite sides of the gear-wheel G⁶ are segmental or interrupted gear-wheels G⁸ and G⁹, which are adapted to respectively mesh with pinions H and I upon parallel shafts H' and I'. H² is a gear-wheel on the shaft H' intermeshing with a pinion H³, which is on a shaft D' of the lower feed-roll D. The upper feed-roll is driven from the shaft D' through the medium of intermeshing gears J J', so that the two rolls will be driven at the same peripheral speed, while their operation will be timed by the interrupted gear segment G⁸. The shaft I' has mounted thereon, a gear-wheel K, which intermeshes with a pinion K' on the drum-shaft F and drives the drum. Adjacent to the pinion K' and coupled therewith is a gear-wheel K² forming the drive member of a gear-train L for driving the feed rolls L' and L² for the metallic reinforcement. M is a shaft adjacent to the lower feed roll L² for controlling the operation of said feed rolls, and which is itself driven by a sprocket-and-chain connection M' from the main shaft G⁷. Suitable locking mechanism is provided for each of the shafts H' and I' when not in operation—such as star-wheels H⁴ and I⁴ on the main shaft G⁷ en-

gaging roller pin-wheels H^5 and I^5 respectively on the shafts H' and I' .

Winding mechanism.—The drum C is provided with grippers C^3 which are adapted to engage with the forward edge of the paper strip when fed off from the table E . These grippers are operated by a rock-arm C^4 having a roll C^5 which engages a circular track C^6 concentric with and within the drum shaft, said track being cut away at one point to permit the dropping of the roll C^5 and opening of the grippers when the drum is in its initial position, and also having a bridge C^{14} for filling said opening when the grippers retain their engagement for more than one revolution of the drum. The detail construction of this mechanism is fully described in the prior patent above referred to, and it is therefore only necessary to state that after once engaging with the paper the grippers retain their engagement during the subsequent rotation of the drum until the requisite number of plies have been wound thereon. As shown and described in the prior patent, above referred to, the drum segments are collapsed and expanded by a toggle-lever C^7 operated by longitudinally-movable bars C^8 connected by links C^9 to a sliding sleeve C^{10} actuated by a lever, C^{11} . The feeding of the paper strip is effected by the rolls D which, as already stated, are driven from the gear-segment G^8 when in mesh with the pinion H . This segment is so positioned and timed that the paper will start feeding at the same time that the gear-segment G^9 , engaging with the pinion I , starts the rotation of the drum. The paper is positively fed by the rolls D at the same speed as the drum until the grippers are operated to engage the forward edge of the paper strip. The segment G^8 then disengages from the pinion H and permits the further feeding of the paper to be effected by the winding of the drum, while the frictional resistance will be just sufficient to maintain the proper tension. To cement the plies of paper to each other a paste-roll N is arranged beneath the table E and is adapted to be pressed upward against the underside of the paper strip. This roll is, however, lowered out of contact with the strip during its initial movement and until a length has been fed equal to one convolution upon the drum, thereby avoiding the pasting of the paper to the drum. The roll N is then raised and continues to apply the adhesive to the underside of the strip until the full length has been applied, the mechanism for accomplishing this being preferably constructed as follows: O is a tank for the adhesive, in which the roll N is partially immersed; O' are rock arms, at the free end of which the roll N is journaled; and O^2 are cams engaging the arms O' to raise and lower the same. The cams O^2 are mounted

upon a rock shaft O^3 , actuated by a rock arm O^4 from a cam O^5 upon the main shaft G^7 . Means is also provided for rotating the roll N whenever it is lowered out of contact with the paper strip, this consisting of gear or friction wheels N' and N^2 , which engage when the roll N is lowered but which are disengaged by the raising of the roll. Thus where an adhesive is employed which will quickly harden when exposed to the air—such as silicate of soda—incrustation of the surface of the roll is prevented by this constant movement.

Reinforcement applying mechanism.—The metallic reinforcement, which is wound between the plies of the paper or fiber stock is preferably a flat sheet of open-mesh expanded metal. This is placed upon the table B and is fed by the operator against a stop, P , which permits a portion of the sheet to extend between the upper and lower feed rolls L' and L^2 . The cam M^2 upon the shaft M engages a roller P' upon a rock-frame P^2 which carries the lower feed roll L^2 and is adapted to raise and lower said frame and roll. The timing is such that during the initial movement of the paper stock, the roll L^2 is lowered and consequently is out of contact with the metallic reinforcement, while the contact of the upper roll L' is insufficient to feed the sheet. At the proper time, the cam M^2 will raise the frame P^2 and the roll L^2 , pressing the latter against the underside of the sheet and causing it to travel forward, the stop P which is mounted upon the rock frame P^2 being raised out of the path of the sheet. The sheet thus fed will pass around a segmental guide Q which imparts a curvature thereto and finally directs it so as to tangentially engage the winding-drum near the point of tangency of the paper strip. The feeding continues until the reinforcement is firmly gripped between the plies of the paper, after which the cam M^2 again lowers the roll L^2 and permits the further feeding to be effected by the drum.

It is desirable to coat with the adhesive the side of the metallic reinforcement which comes in contact with the uncoated side of the paper. This is accomplished by feeding the reinforcement upward through a well in the tank O and into contact with a roll R , which is partially immersed in the tank. The reason for this arrangement is that it is desirable to avoid applying the adhesive to the guides or any other part of the machine, and therefore the roll R is located adjacent to the point of engagement between the reinforcement and the plies of paper on the drum, while the passing of the reinforcement through the well in the tank permits of using the one tank for both the rolls R and N . To press the reinforcement in firm contact with the paper ply on the drum a spring-pressed guide or shoe S is arranged

adjacent to the drum; but spaced therefrom sufficiently to permit one or more convolutions of paper being wound without contacting with said guide. The added thickness of the reinforcement and the second ply of the stock will bring the latter in contact with the guide, which will operate as a presser and will hold the plies from springing outward.

19 *Cut-off mechanism.*—Before the completion of the winding the paper strip must be severed, which operation is performed by a knife-bar T located above a slot in the table E and in co-operative relation with a stationary shear-blade. The knife-bar is actuated by internal cams S' and S² upon the main shaft G⁷ which engage rolls S³ upon the knife-bar carrying-frame S⁴, and at the proper point in the cycle lugs S⁵ on said cams depress said rolls to cause the knife to sever the strip. During this severing operation the rotation of the drum is arrested by an interruption G¹⁰ in the gear-segment G⁶, thereby avoiding straining or danger of 25 tearing the paper strip; but as soon as the strip is severed that drum is again rotated to complete the winding. In starting the operation it is necessary to trim the end of the strip square, and for this purpose the 30 knife-bar may be manually operated through a pedal U connected by the link U' with the frame S⁴.

35 *Operation.*—After the engagement of the paper strip with the feed rolls D and the trimming of the end portion thereof by the 40 manual operation of the pedal U, the metallic reinforcing sheets are placed upon the table B and the machine is ready for operation. The operator first adjusts the reinforcement sheet between the rolls L' and L², which in the position of rest of the machine are separated, and the stop P properly positions the forward edge of the sheet. The drum C may be in a position where its segments are collapsed for the removal of the 45 previously formed package, in which position the roll C⁵ is in engagement with the notch C¹² in the circular track C⁶. In the initial movement of the drum, however, the roll C⁵ travels up the cam side of the notch and engages the circular track C⁶, whereby the roll not only fastens the clips C³, but also expands the drum when collapsed by forcing outward the segment C² thereof. 50 That is, the segments of the drum when collapsed are in close proximity to the circular track, so that the roll traveling upon the track engages the segments, thereby forcing them outward. This movement is assisted by a spring C¹³ drawing upon the toggle levers C⁷ to straighten the same. This operation will positively expand the drum so as to avoid any danger of winding the paper about the drum in collapsed position. To 55 start the operation the clutch G⁸ is engaged

by the manual operation of a pull-rod or other control device V. This is so arranged that the clutch when thrown into engagement will continue to drive the mechanism until one complete revolution is performed, 70 upon which the clutch is again disengaged automatically by suitable mechanism, not shown. The movement of the shaft G⁴ driven by the clutch will be transmitted through the pinion G⁵ and gear-wheel G⁶ to 75 the main shaft G⁷, from which in turn it is intermittently transmitted to the shafts H' and I' by the interrupted gear-segments G⁸ and G⁹ as previously described. During the initial movement the segment G⁸ will 80 actuate the pinion H on the shaft H' and will impart movement to the feed rolls D, which will advance the paper strip until its forward edge comes in contact with the grippers C³. Just prior to this contacting of the strip with the grippers the gear segment G⁹, engaging the pinion I upon the shaft I', will communicate motion through the gear-wheels K and K' to the drum-shaft, causing the rotation of the drum at the same peripheral speed as the speed of the paper strip. The rotation of the drum will cause movement of the roll C⁵ out of the notch C¹² in the stationary cam C⁶, which, as above described, will positively expand the drum and effect the engagement of the grippers with the edge of the paper strip. The drum then continues to rotate until the feed rolls D cease to be positively driven by the disengagement of the gear-segment G⁸ from the 90 pinion H, after which the paper is fed solely by the winding drum.

95 During the movement thus far described, the paste-applying roll N is in its lowermost position within the tank O, and is out of contact with the paper strip, but the cam O⁵ which, through the medium of the rock arm O⁴, shaft O³, and cam O², operates the rock-arms O' to raise the roll N, is so timed that as soon as a length of paper sufficient to 100 form one complete convolution has passed the point opposite the paste-roll, the latter is raised and applies the adhesive to the underside of the paper strip. The metallic reinforcement, which has been stationary on the table B during the initial operation, is 105 actuated by the pressing of the lower feed roll L² against the upper feed roll L', which is effected by the cam M² engaging the roll P' on the rock-frame P², this also disengaging the stop P. The sheet will thus be fed up around the curved guideway Q and through the slot or well in the paste receptacle O. It will then be directed rearward by the curvature of the guide and into contact with the roll R, which, being immersed in the liquid adhesive, will coat the lower surface of the reinforcement as previously described. The strip will then be fed in between the convolution or convolutions of paper pre- 110 115 120 125 130

- viously wound upon the drum and the portion of the strip still being wound thereon, and thus will be embedded between the plies with liquid adhesive on both sides thereof to cement it to the paper. The increased thickness of the windings will bring the same into contact with the resiliently-pressed shoe S which acts as a presser-bar for maintaining the convolutions in firm contact.
- 10 At the point in the operation where the full length of paper strip is passed forward of the plane of the knife-bar, movement of the drum is temporarily arrested by the interruption G^{10} in the gear-segment G^9 , and
- 15 at the same time the lugs S^5 on the cams S^1 , S^2 operating upon the rolls S^3 on the knife-carrying frame S^4 , will depress the knife-bar T and cause the severance of the sheet. Movement is then again imparted to the
- 20 drum and continued until the winding is complete, whereupon the segments of the drum may be collapsed by the operation of the lever C^{11} , which indirectly bends the toggle-levers, thereby bringing in the drum
- 25 segments toward the center of the drum, and the completed reinforced cylindrical package may be removed from the drum. This completes the cycle and the operation may be repeated by again actuating the controller V and tripping the clutch.
- 30 What I claim as my invention is:—
1. A machine for winding reinforced cylindrical packages, comprising a winding-drum, means for feeding a sheet of paper or fiber stock into engagement with said drum from one side thereof, means for feeding a reinforcement from the opposite side to said drum, and a guide for directing said reinforcement into engagement with the
- 35 drum beneath the sheet of paper or fiber stock.
- 40 2. A machine for winding reinforced cylindrical packages, comprising a winding-drum, means for feeding a strip of fiber stock tangentially to said drum and into engagement therewith, and means for feeding a reinforcement sheet beneath said strip of paper or fiber stock into engagement with said drum, operating after the winding of
- 45 one or more complete convolutions of the paper stock on said drum.
- 50 3. A machine for winding reinforced cylindrical packages, comprising a winding-drum, means for feeding a sheet of fiber stock tangentially into engagement with said drum, means for feeding a reinforcing sheet beneath said fiber strip into contact with said winding-drum subsequent to the winding of one or more convolutions thereon, and
- 55 means for applying adhesive to one of the contacting faces of both the paper stock and the reinforcement.
- 60 4. A machine for winding reinforced cylindrical packages, comprising a winding-drum, means for feeding a sheet of paper

or fiber stock tangentially into engagement with said drum, means for feeding a sheet of metallic reinforcement beneath said paper or fiber strip tangentially into engagement with said drum subsequent to the winding of one or more convolutions of the paper stock thereon, means for applying adhesive to that portion only of the paper or fiber stock which is wound over the first convolution, and means for also applying adhesive to the face of the metallic reinforcement which is opposite that contacting with the adhesive-coated face of the paper or fiber strip.

5. A machine for winding reinforced cylindrical packages, comprising a winding-drum, means for feeding a paper or fiber strip tangentially into engagement with said drum, means for feeding a flat sheet of metallic reinforcement in the opposite direction and from the opposite side of said drum, and a guide for directing said reinforcement sheet into contact with said drum beneath said paper strip and for imparting thereto a curvature facilitating its winding upon the drum.

6. A machine for winding reinforced cylindrical packages, comprising a winding-drum, means for feeding a sheet of paper or fiber stock tangentially into engagement with said drum, means for feeding a flat sheet of metallic reinforcement, and a curved guide through which said metallic reinforcement is fed imparting a curvature thereto and directing its forward edge tangentially into contact with said drum beneath said paper or fiber sheet.

7. A machine for winding reinforced cylindrical packages, comprising a winding-drum, means for feeding a paper or fiber sheet tangentially into engagement with said drum, means for also feeding a flat sheet of metallic reinforcement, a guide through which said metallic reinforcement is fed for directing the same tangentially into contact with said drum beneath said paper or fiber strip and for imparting a curvature thereto, and means for applying adhesive to the under faces of said paper or fiber strip and said metallic reinforcement.

8. A machine for winding reinforced cylindrical packages, comprising a winding-drum, means for feeding a sheet of paper or fiber stock tangentially into engagement with said drum, means for feeding a flat sheet of metallic reinforcement in the opposite direction and from the opposite side of said drum, and a guide for curving said flat sheet and for changing the direction of travel thereof to engage the same with said drum at the point of tangency of said paper or fiber stock.

9. A machine for winding reinforced cylindrical packages, comprising a wind-

ing-drum having means of engagement with a strip of paper or fiber stock to wind the same thereon, feed rolls rotating continuously with the rotation of said drum, and mechanism for pressing said rolls into feeding contact with said sheet, timed to feed the reinforcement into contact with said drum after one or more convolutions of said paper stock have been wound thereon.

10 10. A machine for winding reinforced cylindrical packages, comprising a collapsible winding-drum, means for feeding a sheet of paper or fiber stock tangentially into engagement with said drum, and means operating upon the initial rotary movement of said drum for positively expanding the same from its collapsed position.

11. A machine for winding reinforced cylindrical packages, comprising a winding-drum, means for feeding a sheet of paper or fiber stock tangentially into engagement with said drum, a pair of feed rolls constantly rotating with the rotation of said drum, said rolls being separated for the insertion of a metallic reinforcement sheet therebetween, a stop for positioning said sheet when inserted between said rolls, and timed mechanism for pressing said rolls

into engagement with said sheet and simultaneously withdrawing said stop. 30

12. A machine for winding reinforced cylindrical packages, comprising a collapsible winding-drum, manually operable means for collapsing said drum, a tension device for assisting in expanding said drum, and means operating upon the initial rotary movement of said drum for positively expanding the same. 35

13. A machine for winding reinforced cylindrical packages, comprising a winding-drum, means for feeding a paper or fiber strip tangentially into engagement with said drum, means for feeding a reinforcement in the opposite direction and from the opposite side of said drum, means for directing said reinforcement into contact with said drum beneath said paper strip, and constantly rotating means for applying adhesive to said paper strip and 50 reinforcement.

In testimony whereof I affix my signature in presence of two witnesses.
